PARAMOUNT KNITTING COMPANY, OF CHICAGO, ILLINOIS, A CORPORATION OF
ILLINOIS.

KNITTING-MACHINE NEEDLE.

1,241,882.

Specification of Letters Patent.

Patented Oct. 2, 1917.

Application filed December 7, 1915. Serial No. 65,602.

To all whom it may concern:

Be it known that we, FRANK POPE and EDISON E. RANDALL, both citizens of the United States, residing at Kankakee, county 5 of Kankakee, State of Illinois, have invented an Improvement in Knitting-Machine Needles, of which the following description, in connection with the accompanying drawing, is a specification, like characters on the 10 drawing representing like parts.

This invention relates to a knitting machine, and particularly to the needle and the means for operating it, and more particularly to the type of mechanism made 15 the subject of our Patent No. 1,096,946 granted May 19, 1914 wherein the needle comprises a hook member and a latch member physically independent and separate from each other, although co-acting to perform the required knitting functions.

The object of the invention is to provide in a machine of this type a construction in which the movement of the needle members will be secured with accuracy and with a 20 minimum amount of wear.

While this type of machine and needle is suitable for a wide range of use in various kinds of knitting machines, including both the cylinder and the dial of circular knitting machines, it has a peculiar value in the 30 dial of a circular machine because it enables the finest class of work to be performed.

In ribbed knitting, for example, in the knitting of stockings, the dial needles are 35 supported in a circular course inside of the circular path of the cylinder needles. Hence the number of dial needles which can be employed is limited, the main limitations being the length of the needle, the length 40 of its movement necessary to enable it to perform its looping function, and the space available for the inner tail ends of the needles.

The construction illustrated in our prior 45 Patent No. 1,096,946 disclosed as a specific embodiment of the invention a latch member having its shank bent so as thereby to produce the necessary friction in the slot for the latch member. This was essentially 50 an unsymmetrical arrangement and under usual conditions would cause the laterally contacting parts of the hook and latch member to wear materially.

It is the more specific object of the present 55 invention to provide a construction in which

the latch member shall move in the same longitudinal plane as the hook member and be subject to no influence materially tending to deflect it from this relation and thus shall insure the co-operative movement of the two 60 members of the needle freely, easily and with a minimum amount of wear.

Another object of the invention is to provide a construction in which the outer or head end of the latch member is out of contact of the side walls of its groove, and is thus free to conform to the longitudinal path of movement of the hook member.

These and other objects of the invention will appear more fully from the accompanying 70 description and drawings and will be particularly pointed out in the appended claims.

The drawings illustrate so much of a dial of a circular knitting machine as is necessary to a disclosure of this invention although it will be understood that the invention is not to be limited to the particular type of knitting machine nor to the particular part of the knitting machine, but may be 75 employed wherever knitting machine needles are used.

In the drawings,

Figure 1 is a central vertical cross section of a portion of a needle dial of an ordinary 80 type of circular knitting machine with a preferred form of the present invention embodied therein;

Fig. 2 is a top plan view enlarged as to 85 diameter and greatly exaggerated circumferentially of a portion of the needle bed, constructed as shown in Fig. 1;

Fig. 3 is a view similar to Fig. 2 showing a slightly different construction embodying the invention;

Fig. 4 is a view similar to Fig. 1 showing a third construction embodying the invention;

Fig. 5 is a top plan view enlarged and exaggerated as in Fig. 2 of a portion of the 100 needle bed shown in Fig. 4 after the needle and latch grooves have been formed;

Fig. 6 is a view similar to Fig. 5 after the structure has been completed and the 105 needles are in place.

It is unnecessary to describe any portion of a knitting machine except that portion directly adjacent the needles because the general structure of the knitting machine or the particular type thereof forms no part of 110

the present invention. The invention is herein shown as applied to the dial of a circular knitting machine and certain terms of position and direction are used herein because of that fact, but the invention is applicable to other types of knitting machines and to constructions in which the needles move in other than horizontal and radial paths, and in its broader aspects the invention is thus to be construed.

In the construction illustrated, and referring first to that embodiment of the invention illustrated in Figs. 1 and 2, the usual stud 1 carries the needle bed 2 in which the needles are mounted and operate. The cam member is shown as consisting of two concentric parts 3 and 4 between which is formed the usual cam groove 5 for receiving the butts of the needles and securing their operation.

The needles are of the type shown in our prior Patent No. 1,096,946 and each comprises a hook member 6 and a latch member 7. The hook member has a generally similar form to the corresponding member of the ordinary pivoted latch needle and comprises the hook 8, the shank 9 and the butt 10. The shank and butt may be of varying length and shape, but in the case of the dial needle and especially where fine work is to be performed the extreme length of the hook member is made as small as possible and the gage of the needle as fine as possible. The shank need not project beyond the butt and the butt may be brought close up toward the hook end, or in fact close up to the slot in the hook member through which the latch member operates, thus making an extremely short needle having the minimum throw. The hook member of this type of needle is slotted at 11 and this slot is preferably made in the form of a saw kerf presenting end walls 12 and 13. The latch member is preferably made of thin sheet metal of a thickness such as will allow it to move readily within the slot 11 and comprises a head 14 and a shank 15. The latch member is provided with cam surfaces at the rear and front of the head coöperating respectively with the walls 12 and 13 of the slot in the hook member.

The shank of the latch member is frictionally engaged so as to secure retardation of the latch member against longitudinal movement except when it is positively moved by the movement of the hook member thus insuring the accurate operation of the needle. The end walls 12 and 13 of the slot in the hook member and the coöperating cam surfaces on the head of the latch member are so shaped and proportioned in accordance with the general principles set forth in our prior Patent No. 1,096,946 that the movement of the hook member longitudinally 65 under the control of its operating cam re-

sults in the required movements of the hook and latch members to secure the proper handling of the yarn. There is thus obtained relative longitudinal and transverse bodily movements of the said needle members to 70 effect their coöperative action.

The needle members are mounted and operate in superimposed grooves formed in the needle bed and in the case of the dial these grooves extend radially. The upper groove 75 carries the hook member and the lower groove the latch member.

In Fig. 2 the radial dimensions are much enlarged over Fig. 1 which is itself much larger in dimensions than the ordinary or smaller sizes of machines. Furthermore, in order to illustrate the invention clearly the dimensions circumferentially of the dial are very greatly exaggerated as will be recognized when it is remembered that the gage 85 or width over all of fine needles is measured by the thousandths of an inch.

The upper groove 16 for the hook member extends radially through the section 17 of the needle bed and is of just sufficient width 90 to enable the hook member to move freely therein. The groove 18 for the latch member extends beneath and parallel with the groove 16 for the hook member and extends through the section 17 of the needle bed and 95 the inner concentric section 19, in both sections lying beneath the groove 16. This latch groove 18 is of materially greater width than the latch member 7, being shown as somewhat more than twice the width, and 100 is of materially less width than the groove 16 for the hook member so as to present in the section 17 of the needle bed shoulders 20 and 21 to support the hook member 9.

Means are provided independent of the 105 latch member to press the tail of the shank 15 against one wall of the latch member groove so as to secure the required frictional retardation of the latch member, but leave the head thereof free to move centrally of 110 the hook member and in alinement with the hook member. This means is preferably a flat thin leaf spring 22 having a lateral bend 23 and an upward projection 24 at its inner or rear end. This spring is comparatively short in length and when placed in the groove for the latch member presses the tail of the shank of the latch member against the wall of the groove. But as the latch member is comparatively long and resilient 120 it is thus free for the main portion of its length and is thus permitted to remain centrally of the hook member with its head projecting through the slot in the hook member and moving in alinement therewith so that 125 there is no wear on the parts. In the construction illustrated in Fig. 2 this result is secured with exact accuracy because the groove for the latch member both in its inner section 19 and its outer section 17 is so 130

positioned that one side wall 25 lies in a plane parallel with the side walls of the groove for the hook member and at a distance to one side the medial plane thereof 5 equal to one-half the thickness of the latch member so that when the latch member is held against the inner section of its groove the latch member will move exactly central of the hook member and parallel therewith. 10 The springs 22 are held in position in any suitable manner and for that purpose a cap 26 is illustrated provided with a circumferential groove fitting over the projection 24. This cap is located concentric of the 15 stud 1 and preferably is so positioned as to leave a space 27 between it and the innermost concentric section 28 of the needle bed into which space lint and dust may work during the operation of the needles without 20 clogging the needles and from which it may be readily removed.

The substantial advantages of the invention may also be secured especially in the finer gages of needles even when there are 25 slight departures from the theoretical accuracies of construction illustrated in Fig. 2. For example, as illustrated in Fig. 3 the groove 29, 30 for the latch member may be 30 cut parallel with but centrally of the groove 16 for the hook member thus leaving the shoulders 31 and 32 of equal width. In this case when the bent spring 33 is inserted to 35 press the tail of the shank 15 of the latch member against one wall of its groove the latch member will have to bend laterally to 40 a very slight extent in order that its head 14 may move centrally of and in alignment with the hook member 6, but as this bending of the latch member is very slight no substantial 45 wear will be produced between the hook and latch members and the latch member will be free throughout the main portion of its length easily to assume the correct position.

45 A third embodiment of the invention in which a very slight departure is made from theoretical accuracy, and yet in which all the substantial advantages of the invention are secured while a ready method of construction is provided, is illustrated in Figs. 4, 5 and 6. As this construction is similar to those already described it will only be necessary to call attention to the points of difference.

55 In this form the inner concentric section of the needle bed is made as a separate part 34 secured in place as by a set screw 35. In constructing the grooves for the hook member and latch member the groove 36 for the hook member is first cut and then the groove 37 for the latch member is cut centrally of 60 and parallel with the groove 36 through both sections of the needle bed as shown in Fig. 5. Then the screw 35 is loosened up 65 and the inner section 34 of the needle bed

shifted circumferentially until the inner section 38 of the latch member groove is offset from the outer section to such an extent as to present one wall, as 39, at a distance to one side of the medial plane of the hook 70 member groove 36 equal to one-half the thickness of the latch member shank, as shown in Fig. 6. In this case the bent leaf spring 40 is entirely located in the inner section 75 38 of the latch member groove and acts to press the tail of the shank 15 of the latch member 7 against the wall 39, thus securing the desired frictional retardation of the latch member and enabling the head of the latch member to move centrally of and in 80 alignment with the hook member. When the inner section 34 is thus shifted to the required position it is secured in place as by pins 41, and the set screw 35 is tightened up. This construction leaves the shoulders 42, 85 43, upon which the hook member rests, of equal width. When the inner section 34 of the needle bed is shifted the inner section 38 of the latch member groove will not be in mathematical parallelism with the outer section but the difference is so infinitesimal as to be negligible.

Having fully described our invention, what we claim as new and desire to secure by Letters Patent is:

1. In a knitting machine a needle comprising a longitudinally slotted hook member, a separate latch member provided with a shank and with a head passing through the slot of the hook member, means for securing relative, longitudinal and transverse bodily movements of said members to effect the co-operative action of the hook and latch, a needle bed provided with superimposed grooves for said members, the latch member groove being of materially greater width than the latch member and of materially less width than and extending beneath and parallel with the hook member groove, and means independent of the latch member acting to press the tail of its shank against one wall of its groove whereby the required frictional retardation of the latch member is secured while the head thereof is central of and moves in alignment with the hook member. 115

2. In a knitting machine, a needle comprising a longitudinally slotted hook member, a separate latch member provided with a shank and with a head passing through the slot of the hook member, means for securing relative, longitudinal and transverse bodily movements of said members to effect the co-operative action of the hook and latch, a needle bed provided with superimposed grooves for said members, the latch member groove being of materially greater width than the latch member and of materially less width than and extending beneath and parallel with the hook member 130

- groove, and a spring located in the latch member groove separate from the latch member and acting to press the tail of the shank of the latch member against one wall 5 of its groove, whereby the required frictional retardation of the latch member is secured while the head thereof is central of and moves in alignment with the hook member.
- 10 3. In a knitting machine a needle comprising a longitudinally slotted hook member, a separate latch member provided with a shank and with a head passing through the slot of the hook member, means for securing relative, longitudinal and transverse bodily movements of said members to effect the coöperative action of the hook and latch, a needle bed provided with superimposed 15 grooves for said members, the latch member groove being of materially greater width than the latch member and of materially less width than and extending beneath and parallel with the hook member groove, and a spring device located in the latch member 20 groove separate from the latch member and acting to secure the required frictional retardation of the latch member while the head thereof is central of and moves in alignment with the hook member.
- 25 30 4. In a knitting machine a needle comprising a longitudinally slotted hook member, a separate latch member provided with a shank and with a head passing through the slot of the hook member, means for securing 35 relative, longitudinal and transverse bodily movements of said members to effect the coöperative action of the hook and latch, a needle bed provided with superimposed groove for said members, the latch member 40 groove presenting an inner and an outer section, one side wall of the inner section lying in a plane substantially parallel with the side walls of the outer section and at a distance to one side the medial plane thereof 45 equal to one-half the thickness of the latch member shank, and means for maintaining a frictional engagement between said wall of the inner section and said shank whereby the required frictional retardation of the latch 50 member is secured while the head thereof is central and moves in alignment with the hook member.
5. In a knitting machine needle comprising a longitudinally slotted hook member, a 55 separate latch member provided with a shank and with a head passing through the slot of the hook member, means for securing relative, longitudinal and transverse bodily movements of said members to effect the coöperative action of the hook and latch, a needle bed provided with superimposed 60 grooves for said members, the latch member groove presenting an inner and an outer section, one side wall of the inner section 65 lying in a plane substantially parallel with the side walls of the outer section and at a distance to one side the medial plane thereof equal to one-half the thickness of the latch member shank, and a spring located in the latch member groove and acting to hold the latch member in frictional engagement with the said side walls whereby the required frictional retardation of the latch member is secured while the head thereof is central of and moves in alignment with the hook member.
7. In a knitting machine a needle comprising a longitudinally slotted hook member, a separate latch member provided with a shank and with a head passing through the slot of the hook member, means for securing relative, longitudinal and transverse bodily movements of said members to effect the coöperative action of the hook and latch, a circular needle bed comprising inner and outer concentric sections, superimposed 105 grooves for said members formed in and radially of said bed, the groove for the latch member extending into both sections of the needle bed with that portion of the said groove in the inner section offset laterally to present one of its side walls to one side of the medial plane of the outer section a distance equal to one-half the thickness of the latch member, a spring rotated in the inner section of the inner groove acting 110 to hold the latch member in frictional engagement with the said side wall whereby the required frictional retardation of the latch member is secured while the head thereof is central of and moves in alignment with the hook member.
8. In a knitting machine a needle comprising a longitudinally slotted hook member, a separate latch member provided with a shank and with a head passing through the 115

slot of the hook member, means for securing relative, longitudinal and transverse bodily movements of said members to effect the co-operative action of the hook and latch, 5 a circular needle bed comprising inner and outer concentric sections, superimposed grooves for said members formed in and radially of said bed, the groove for the latch member extending into both sections 10 of the needle bed with that portion of the said groove in the inner section offset laterally to present one of its side walls to one side of the medial plane of the outer section a distance equal to one-half the thickness 15 of the latch member, a bent leaf spring located in the inner section of said groove contacting with and acting to press the latch member in frictional engagement with the said side walls whereby the required frictional retardation of the latch member 20 is secured while the head thereof is central of and moves in alinement with the hook member.

9. In a knitting machine a needle comprising a longitudinally slotted hook member, a separate latch member provided with a shank and with a head passing through the slot of the hook member, means for securing relative, longitudinal and transverse 25 bodily movements of said members to effect the co-operative action of the hook and latch, a circular needle bed comprising inner and outer concentric sections, superimposed grooves for said members formed in and 30 radially of said bed, the groove for the latch member extending into both sections of the needle bed with that portion of the said groove in the inner section offset laterally to present one of its side walls to one 35 side of the medial plane of the outer section a distance equal to one-half the thickness of the latch member, a bent leaf spring located in the inner section of said groove 40 contacting with and acting to press the latch member in frictional engagement with the said side walls whereby the required frictional retardation of the latch member 45 is secured while the head thereof is central of and moves in alinement with the hook member, a central cap, and means effecting an intimate engagement between the cap and 50 spring to maintain the spring in position.

10. In a knitting machine a needle comprising a longitudinally slotted hook member, a separate latch member provided with a shank and with a head passing through the slot of the hook member, means for securing

relative, longitudinal and transverse bodily movements of said members to effect the co-operative action of the hook and latch, and 60 means for frictionally engaging the shank of the latch member and maintaining the head of the latch member central of and in alinement with the hook member during the co-operative movement of the hook and latch 65 members.

11. In a knitting machine a needle comprising a longitudinally slotted hook member, a separate latch member provided with a shank and with a head passing through the slot of the hook member, means for securing relative, longitudinal and transverse bodily 70 movements of said members to effect the co-operative action of the hook and latch, a needle bed provided with superimposed 75 grooves for said members, and a separate spring acting to frictionally engage the shank of the latch member with the inner section of its groove and maintain the head of the latch member central of and in alinement with the hook member during the co-operative movement of the hook and latch 80 members.

12. In a knitting machine a needle comprising a longitudinally slotted hook member, a separate latch member provided with a shank and with a head passing through the slot of the hook member, means for securing relative, longitudinal and transverse bodily 85 movements of said members to effect the co-operative action of the hook and latch, a circular needle bed comprising inner and outer concentric sections, superimposed 90 grooves for said members formed in and radially of said bed, the groove for the latch 95 member extending into both sections of the needle bed, means for securing the inner section of the needle bed in circumferential displacement with respect to the outer section of the needle bed to cause the latch 100 member to project in and move centrally of that section of its groove in the outer section of the needle bed, and means located in the inner section of the latch member groove 105 acting to hold the latch member in frictional engagement with one of the side walls of its groove whereby the required frictional retardation of the latch member is secured.

In testimony whereof, we have signed our 110 names to this specification.

FRANK POPE.
EDISON E. RANDALL.
